United States Patent

Des. 240,844
Patented Aug. 3, 1976

240,844

MUSICAL TOY

Michael I. Satten, 245—20 Grand Central Parkway,
Bellrose, N.Y. 11362

Filed Jan. 23, 1975, Ser. No. 543,405

Term of patent 14 years

Int. Cl. D21—01

U.S. Cl. D34—15 C

FIG. 1 is a front elevational view of a musical toy showing my new design;

FIG. 2 is a right side elevational view thereof;

FIG. 3 is a left side elevational view thereof;

FIG. 4 is a rear elevational view thereof;

FIG. 5 is a top plan view thereof; and

FIG. 6 is a bottom plan view thereof.

I claim:

The ornamental design for a musical toy, as shown.
